CARDING-ENGINE.

1,160,367.

Specification of Letters Patent.

Patented Nov. 16, 1915.

Application filed May 1, 1915. Serial No. 25,219.

To all whom it may concern:

Be it known that I, EDDO V. BATES, a citizen of the United States, residing at Lowell, in the county of Middlesex and State of Massachusetts, have invented certain new and useful Improvements in Carding-Engines, of which the following is a specification.

This invention relates to carding engines 10 of the type generally used for carding wool and similar fibers.

Carding engines have heretofore generally included a main cylinder or swift around which were arranged various strippers and workers. Attempts have been made to dispense with the main cylinder but generally such a main cylinder of large size and traveling at a high rate of speed has been used. The teeth of such cylinders considered with reference to the top thereof and to the direction in which the stock was traveling from the receiving to the delivering ends of the machine, have always pitched forward. Around such cylinder 25 have been arranged one or more workers with teeth point to point with those on the main cylinder and one or more strippers which engaged the workers and had teeth back to point with those on the main cylinder. The surface speed of some or all of the workers was very slow compared with that of the main cylinder, one result of which was a breaking and tearing of the stock between the very fast roll and the very 30 slow roll. Another result of this arrangement was that to clear the workers, the strippers must run at a faster speed, and to clear the strippers, the main cylinder must run still faster than the strippers. A further 35 result of this arrangement was that the stock was pulled in tight into the teeth of the main cylinder and was with difficulty cleared therefrom by the fancy, doffer and comb.

I prefer to use a relatively large main cylinder because the angular relation of a large cylinder to the other rolls is smaller and the danger of breaking the stock is therefore reduced. With my arrangement of main cylinder, there is practically no chance of un- 45 carded stock being forced into the teeth and carried along to the doffer for the reason that the teeth of my main cylinder rake backward instead of forward and I run my main cylinder at a low rate of speed. In- 50 stead of traveling at a surface speed of 1,000

feet per minute more or less, I gear or rig my main cylinder to travel from ten to fifty feet per minute more or less. It will be readily understood that such a cylinder can be easily cleared by suitable rolls running at 60 a relatively low speed, if desired.

I find it desirable to arrange strippers, workers and other rolls in groups and in such a manner that the stock on the main cylinder will be cleared off entirely one or 65 more times, preferably two or three times, between the receiving side and the doffer. I can so arrange my delivery rolls that part of the stock will pass under and back with the main cylinder or so that it will all be 70 cleared off. I arrange my rolls in such manner that there is no clogging of the main cylinder at any time and I prefer to arrange them in groups of substantially three or four principal rolls around the main cylinder. 75

In a card of my construction, the centrifugal force of the main cylinder is greatly reduced with the speed, whereby there is little throwing off of stock onto the floor, or other waste. The stock is mixed and blended 80 much better as it all comes off and goes on again several times. The mixing is so much better that I need no second breaker thereby saving a large amount of floor space and power. I also prefer to arrange my rolls 85 which card so that the first rolls which receive the stock and card it shall have a comparatively low separating speed at the point of carding contact, whereby the stock is much less likely to be injured or broken. I 90 prefer to use a large tumbler or tumbler worker running at a relatively slow speed for this reason, and for the reason given above for preferring a large main cylinder, to reduce the angular relation with adjoining rolls. It is also more convenient in arranging the rolls so as to include the first worker of the first group of rolls. I prefer 95 large strippers also as they can be run more slowly than small strippers and the stock does not wind up on them. 100

My arrangement of rolls is, in general, in groups wherein the first to receive the stock travels faster than the main cylinder but with relative slowness while the succeeding two or three principal rolls of each group travel faster. From the last and fastest roll, the stock is removed by means of a fancy and doffer and returned to the main cylinder, or it is taken off directly by simi- 105 110

lar means. In either event, it is carried along to the slowest running roll of the next group by the main cylinder. With each group, in proper relation, I prefer to use a slow running worker running at from ten to twenty feet surface speed per minute in connection with the other rolls which run at from 100 to 900 feet per minute. With my arrangement, I expect with eight principal rolls, eight carding points, with nine principal rolls, nine carding points or in other words at least one carding point for each principal roll, and all the stock is reworked. By principal rolls, I mean those rolls, exclusive of the main cylinder, which do not serve merely as feed rolls, bur rolls, fancies, transfer rolls, or doffers.

The principal feature of my invention is the main cylinder with teeth which pitch 20 backward instead of forward and which runs at a low speed instead of at a high speed together with one or more rolls in operative relation therewith for working the stock. More particularly, it is such a cylinder 25 with one or more groups of rolls each group having one or more rolls, the rolls being so arranged that the main cylinder is stripped clear of stock at one or more points. Still more specifically, it is such a cylinder 30 with such groups, wherein the rolls are smaller than the main cylinder one or more being in carding contact with the main cylinder and the other rolls being arranged for assisting such roll or for reworking the 35 stock. Preferably each group comprises a plurality of principal rolls some of which run at successively higher speeds from the point of receiving to the point of delivering the stock, and preferably in connection 40 with one or more delivery rolls, for clearing the fastest roll of each group. Preferably also each group comprises a slow running worker which engages two of the other principal rolls.

45 In the drawings, I show three types of cards with my invention in operation, but it may be applied in various other ways which will naturally suggest themselves.

In the drawings, Figure 1 is a diagrammatic side elevation of a card embodying my invention with the rolls arranged in groups of substantially equal size, such groups being arranged around the main cylinder, and separated one from the other. Fig. 2 is a diagrammatic side elevation of a card embodying my invention wherein the rolls are arranged in groups of substantially equal size, such groups not being separated, however, but being so arranged that the last 60 roll of one group engages the first roll of the next group. Fig. 3 is a diagrammatic side elevation of a card embodying my invention wherein the arrangement of rolls in the groups is somewhat modified and in 65 which the number of rolls is reduced and

also in which two groups are brought together by the elimination of other rolls.

In all the drawings, A represents the frame, B represents the main cylinder, C and D represent feed rolls, E represents the 70 stripper for feed rolls, F represents the bur clipper, G represents the licker-in or bur roll, H represents the main doffer and K may be called the main or delivery fancy, while L represents the comb. These parts 75 are all substantially of well known construction except the main cylinder which, as stated, has teeth which pitch backward instead of forward and travels at a low surface speed. 80

In referring to the direction of travel of the various rolls, I will use the term "forward" when its top travels from left to right, and "backward" when it travels from right to left. In speaking of the teeth, I 85 will use the terms "pitch forward" or "pitch backward." The feed rolls and bur clipper F are of well known construction as is also the licker-in G. This licker-in has teeth which pitch forward and travels forward at a speed of perhaps 100 feet per minute. In the construction shown in Fig. 1, 11 is a tumbler or tumbler worker which has teeth which pitch backward and which travels backward at a surface speed of perhaps 200 feet per minute, that is, faster than the licker-in. As the main cylinder B travels forward at a surface speed of perhaps 12 feet per minute, the stock 50 will be carded between its teeth and those on the 100 first principal roll or tumbler worker 11. The stock 50 which is received from the feed rolls and licker-in is split at the above carding point into two parts one of which 51 remains on the teeth of 11 and the other 105 of which 52 remains on the teeth of B. Both 51 and 52 are stripped and transferred to the second principal roll 12 which travels at a higher rate of speed than 11, say 400 feet per minute, and has teeth which pitch forward 110 and are in stripping relation with the teeth on B and 11. Between first roll 11 and second roll 12 is a third principal roll 13 which is essentially a worker having its teeth pitch forward and in carding contact with 115 12 and in stripping contact with 11. It preferably travels backward and preferably at a low surface speed such as 12 feet per minute. It must travel more slowly than the roll 12. It cards the stock between itself and 12 and picks up part of the stock 53 120 from 12 and is stripped thereof by 11. This stock 53 merges with 50 and is recorded between 11 and B. The rest of the stock 54 which remains on 12 is brushed up by a 125 long toothed fancy 14 and is removed therefrom by a doffer 15 by which it is replaced upon the main cylinder. The teeth of this doffer preferably pitch forward and it travels backward at a low surface speed but 130

at a faster speed than the main cylinder as say 20 feet per minute. There is a space between this group and the next group, of which the first roll 20, which corresponds with 11, has teeth which pitch backward and runs backward at a similar speed to 11. A second roll 21 which corresponds with 12 has teeth which pitch in the same direction and travels in the same direction at about the same relative speed. The third roll 22 is a worker which corresponds with 13, has teeth which pitch forward in the same way, and travels at about the same relative speed. The other members of the group are the fancy 23 which corresponds with 14 and the doffer 24 which corresponds with 15. The stock is blended and carded by this group in substantially the same way as by the first group, being reworked and replaced on the main cylinder in the same manner. There is space between this group and the third group which comprises the rolls 30, 31 and 32 which correspond in pitch of teeth, direction of travel and speed with 20, 21 and 22 and 11, 12 and 13. The fancy, which may be called the main fancy, K corresponds with 23 and 14 but the main doffer H which corresponds with 24 and 15 is out of engagement with the main cylinder whereby the stock S instead of being returned to the main cylinder is removed by the comb L in a well known manner. It will be observed that the speed of the second principal roll increases over the first and it will be observed that the stock is entirely stripped from the main cylinder by each group, that is, at three points, and that when the teeth of the main cylinder engage the teeth of roll 11, they are clear of stock. In this construction, there are carding points between 11 and B, between 12 and 13, 12 and 15, between 20 and B, 21 and 22, and 21 and 24, also between 30 and B, 31 and 32, and 31 and H. This makes nine carding points with nine principal rolls.

In the construction shown in Fig. 2, the frame A, main cylinder B and the rolls C, D, E, F, H and K together with comb L are the same and their speeds are the same except that of main cylinder B which I prefer should travel at about 30 feet surface speed per minute. The various speeds are substantially the same and the teeth of the various rolls in the various groups pitch in the same direction with those shown in Fig. 1. In the adjustment, however, the roll 15 is brought up into stripping contact with roll 20 and roll 24 is brought into stripping contact with roll 30. The result of this and of making main cylinder B travel at a surface speed faster than 15 or 24 is that its teeth do not pick up the stock from those rolls, but merely brush by the stock which is stripped by the faster running rolls 20 and 30. Another variation which I show

and which I may use if desired is to set the second principal roll 31 of the third group away from the main cylinder so that instead of stripping that part 56 of the stock which in the carding between the main cylinder and first roll 30 is left on the teeth of the main cylinder, such stock 56 continues along under the main cylinder and is merged with the stock 50 which is taken in by the feed rolls. 75

In the construction shown in Fig. 3, the frame A, main cylinder B, rolls C, D, E, F, G, H and K together with comb L are the same as in the other constructions with teeth pitching in the same direction with those there shown. The main doffer H is shown as somewhat larger and the main cylinder B travels at perhaps 12 surface feet per minute. The first principal roll 11 and the second and third principal rolls 12 and 13 of the first group are the same in pitch of teeth, direction of travel and speed as those in the other two constructions shown. Instead of a doffer such as 15, however, I place a roll 60 which I will call the fourth principal roll, having teeth which pitch backward, in such position that it will be in stripping relation with second principal roll 12 and in carding relation with the main cylinder B. I also find it necessary or desirable to locate a fast running long toothed fancy 61 in such position that it will brush up the stock on the roll 60 so that its teeth will not become filled up. This fourth principal roll should travel 100 faster than 12 at perhaps 800 surface feet per minute. Part of the stock 57 after the carding between roll 60 and B remains on 60 as shown. Between this first group of four principal rolls and the next group, I prefer to leave a space. The next group comprises rolls 20, 21 and 22 whose teeth pitch in the same direction with the same rolls in the other construction shown and which travel in the same direction. The speed of 20 and 21 is preferably, however, less than that of 11 and 12 being perhaps for 20, 100 feet per minute, and for 21, 200 feet per minute. The action of the stock and their action on the stock is the same as before. In this construction or arrangement, I have taken out fancy 23 and doffer 24 and have brought together the groups 20, 21, 22 and 30, 31, 32. In so doing it becomes necessary to increase the speed of 30 so that it will run faster than 21, as perhaps 400 feet per minute. By so doing, this roll which may be considered from one view point to be the fourth principal roll of the second series, replaces 24 as 60 replaces 15 125 and in each case such fourth roll instead of carding with the second roll, strips it and cards with the main cylinder. Roll 32 is the same as before and roll 31 in order to strip 30 is speeded up to perhaps 900 feet 130

per minute. It is preferably adjusted so as to be out of stripping contact with the main cylinder whereby the stock 56 travels underneath with the main cylinder as before described. It will be noted that what I have called the fourth rolls of each group as 60 and 30 travel at a relatively fast speed compared with the slow running doffers 15 and 24. The result of this is that they card with the main cylinder and strip the second roll. A fancy is not necessary for roll 30 as it is with roll 60 because roll 30 is thoroughly stripped by the fast running roll 31 whose teeth are kept clear by main doffer H.

The carding points in the construction shown in Fig. 2 are the same as those shown in Fig. 1, that is nine or one for each principal roll. In the construction shown in Fig. 3, however, I have only eight carding points as follows: between 11 and B, 12 and 13, 60 and B, 20 and B, 21 and 22, 30 and B, 31 and 32, 31 and H. In this construction, I dispense with one doffer and one fancy and bring my rolls together more compactly whereby a smaller main cylinder may be used, or with a larger main cylinder, other series or groups of rolls might be used.

It is an advantage in setting to have one or more spaces between various groups and it is an advantage with some kinds of stock to set the main doffer and the last roll of the last series away from the main cylinder so that foreign matter such as chives and dirt can drop to the floor. This last arrangement also permits a complete reworking of part of the stock and as the main cylinder travels slow there is little or none of the fiber thrown off onto the floor by centrifugal force as is the case with a fast running main cylinder.

It will be observed that with the successively increasing speed of the rolls in each group and especially with the relatively low speed of first roll or tumbler 11, the stock is more gently handled than between a slow running worker and a very fast main cylinder as is the arrangement on ordinary cards.

The result is much less breaking of stock.

I prefer in connection with my main cylinder to use groups of rolls which will not only card therewith but will card with each other whereby the stock will be worked, reworked and blended more completely and in a smaller space than if single workers and strippers in pairs were used. Such an arrangement in pairs may be made if desired.

For replacing the stock on the main cylinder, I find it desirable to use a long toothed fancy to brush up the stock on the doffer or roll which takes the place thereof unless, as in the construction shown in Fig. 3, two groups are brought together in such a manner that the last roll of the first group and

the first roll of the last group come together with the latter traveling enough faster than the former to strip it. With such a construction, the fancy and doffer between these groups may be dispensed with and the fancy and doffer of the last group may do the work.

The construction shown in Fig. 3 combines many advantages as, for instance, it is more compact at the same time that the fastest rolls of each group can be operated within a reasonable limit of speed while the space between the groups makes the rolls easier to set. This construction may be regarded as two groups, of four and six principal rolls, wherein of the second group, roll 30 may be regarded as the fourth, roll 31 as the fifth, and roll 32 as the sixth principal roll.

I claim:

1. In a carding engine, the combination of a main cylinder which has teeth which pitch backward and which travels forward at a relatively low speed, with a plurality of rolls in operative relation therewith some of which travel at a higher rate of speed than the main cylinder for carding the stock in connection therewith.

2. In a carding engine, the combination of a main cylinder which has teeth which pitch backward and which travels forward at a relatively low speed, with one or more groups of rolls some of which travel at a higher rate of speed than the main cylinder for working the stock in operative relation therewith whereby the main cylinder is stripped one or more times.

3. In a carding engine, the combination of a main cylinder which has teeth which pitch backward and which travels forward at a relatively low speed, with one or more groups of smaller rolls some of which travel faster than the main cylinder for carding the stock.

4. In a carding engine, the combination of a main cylinder which has teeth which pitch backward and which travels forward at a relatively low speed, with one or more groups of smaller rolls some of which travel faster than the main cylinder for carding and for reworking the stock and for stripping it therefrom.

5. In a carding engine, the combination of a main cylinder which has teeth which pitch backward and which travels forward at a relatively low speed, with one or more groups of smaller rolls each group comprising a plurality of principal rolls some of which travel at successively increasing speeds for carding the stock.

6. In a carding engine, the combination of a main cylinder which has teeth which pitch backward and which travels forward at a relatively low speed, with one or more groups of smaller rolls each group comprising

ing a plurality of principal rolls some of which travel at successively increasing speeds for carding the stock, together with one or more delivery rolls for clearing the 5 fastest roll thereof.

7. In a carding engine, the combination of a main cylinder which has teeth which pitch backward and which travels forward at a relatively low speed, with one or more 10 groups of smaller rolls each group comprising a plurality of principal rolls some of which travel at successively increasing speeds for working the stock, together with one or more delivery rolls for clearing the 15 fastest roll thereof and a slow running worker which cards with one of said rolls and is stripped by another thereof.

8. In a carding engine, the combination of a main cylinder which has teeth which 20 pitch backward and which travels forward at a relatively low speed, with one or more groups of smaller rolls each group comprising a plurality of principal rolls some of which travel at successively increasing 25 speeds for working the stock, together with a fancy for each group and a delivery roll therefor.

9. In a carding engine, the combination of a main cylinder which has teeth which 30 pitch backward and which travels forward at a relatively low speed, with one or more groups of smaller rolls each group comprising a plurality of principal rolls some of which travel at successively increasing 35 speeds for working the stock, together with a fancy for each group and another roll which coöperates therewith for clearing the stock from said group.

10. In a carding engine, the combination of a main cylinder which has teeth which pitch backward and which travels forward at a relatively low speed, with one or more groups of rolls each group including a first 40 principal roll whose teeth pitch backward and which travels backward and is in carding relation with the main cylinder, a second principal roll whose teeth pitch forward and which travels forward, such roll being in stripping relation with the main 45 cylinder and with the first principal roll, and a worker in carding relation with one principal roll and in stropping relation with the other principal roll.

11. In a carding engine, the combination of a main cylinder which has teeth which 50

pitch backward and which travels forward at a relatively low speed with two groups of rolls separated from each other, the first group comprising a first principal roll which has teeth which pitch backward and 55 which travels backward and is in carding relation with the main cylinder, a second principal roll which has teeth which pitch forward and which travels forward at a faster speed than the first principal roll and 60 is in stripping relation therewith and with the main cylinder, a third principal roll which travels at a relatively low speed and cards with the second principal roll and is stripped by the first principal roll, a fourth 65 principal roll having teeth which pitch backward and travels backward at a faster speed than the second principal roll and is in stripping relation therewith and in carding relation with the main cylinder, together with a fancy in operative relation 70 with said fourth principal roll, and a second group comprising a first principal roll with teeth which pitch backward and which travels backward and is in carding relation 75 with the main cylinder, a second principal roll with teeth which pitch forward and which travels forward and is in stripping relation therewith and with the main cylinder, a third principal roll which travels at 80 a relatively low speed and is in carding relation with the second principal roll and in stripping relation with the first principal roll, a fourth principal roll which has teeth which pitch backward and which travels 85 backward at a faster speed than second principal roll and is in stripping relation therewith and in carding relation with the main cylinder, a fifth principal roll which has teeth which pitch forward and which travels forward at a faster speed than the fourth principal roll and is in stripping relation therewith, a slow running sixth principal roll which cards with the fifth principal roll and is stripped by the fourth principal roll, together with a fancy in operative relation with the fifth principal roll, and a main doffer which cards with and 90 clears said fifth principal roll.

In testimony whereof I hereto affix my 95 signature in presence of two witnesses.

EDDO V. BATES.
